UNITED STATES PATENT OFFICE.

JOSEPH ASPINALL, OF BOLTON, ENGLAND.

ROPE OR CABLE GRIP FOR HAULAGE PURPOSES.

SPECIFICATION forming part of Letters Patent No. 758,496, dated April 26, 1904.

Application filed May 29, 1903. Serial No. 159,270. (No model.)

To all whom it may concern:

Be it known that I, JOSEPH ASPINALL, agent, a subject of the King of Great Britain and Ireland, residing at 27 Park View road, Daubhill, Bolton, in the county of Lancaster, England, have invented new and useful Improvements in Rope or Cable Grips for Haulage Purposes, of which the following is a specification.

10 This invention relates to improvements in rope or cable grips for haulage purposes, and is more particularly intended for use in the under haulage of "tubs" in coal and other mines, though it may also be applied for other haulage purposes where there is a more or less continuously running or traveling rope or cable, the object of the invention being to provide a gripping device that can be used either for pulling or pushing the tubs, as occasion 15 may require, and at the same time one which can be readily attached to or released from either the cable or rope or the vehicle containing the load to be carried.

My invention consists, essentially, in an 20 open-sided jaw forming one portion of the grip, carrying therein a loose or pivoted jaw which can be forced into contact with the rope or cable by means of a pivoted lever provided with arms or a cam-shaped surface designed 25 to come in contact with the loose or pivoted jaw, whether the lever is pulled or pushed in one direction or the other, the said lever being connected to the load-carrying vehicle either directly or by means of a link, rope, chain, or the like.

30 My invention will be fully described with reference to the accompanying drawings, in which—

Figure 1 is a side elevation of the grip; Fig. 40 2, a sectional elevation on line 12 of Fig. 1; Fig. 3, a side elevation, partly in section; and Fig. 4 a plan on line 34 of Fig. 3.

In carrying out my invention I provide an 45 open-sided jaw *a* of a size sufficiently strong to suit the load to be pulled or pushed and made of any material suitable for the purpose. One portion of the jaw is constructed to embrace the haulage cable or rope *b*, and extending from this portion is another portion, *c*, 50 preferably chambered in such a way as to hold

therein a loose or movable jaw *d*, designed to be capable of being moved toward or from the cable. The jaw may be entirely loose in the chamber or it may be provided with slots or slotted arms *e* at either side, the said arms being formed integral with the jaw or, as indicated in the drawings, merely consist of plates pivoted or riveted or otherwise secured to the jaw *d* at *d'*. *f* represents the slots which embrace a pin *g*, passed through the main portion of the jaw *d* and riveted thereto or loosely secured therein. The slots *f* act somewhat as a guide during the movement of the jaw from the full-line position to the broken-line position, (indicated in Fig. 3,) in which latter position the jaw securely grips the cable between itself and the main portion or jaw *a*. In order to move the jaw *d* toward the cable *b*, I pivot on the pin *g* a lever *h*, provided at that end nearest to the loose or pivoted jaw *d* with 60 projecting arms *i* or a cam-shaped surface or surfaces, while the other end of the lever may be connected to the load-carrying vehicle directly or by means of a link or hook *j*, rope, chain, or the like. As an additional means of 65 guiding the jaw *d* during its movement I may form on the jaw projections *k*, as indicated in Fig. 4.

A gripping device such as I have described is especially suitable for under haulage in connection with coal or other mines, no matter whether the roads or ways are inclined, level, or undulating, as the load itself is the medium by which the loose jaw is caused to approach and grip the cable between itself and the embracing portion of the gripping device, and the latter is of such a character that the load can either be pulled or pushed. At the same time the device can be readily disconnected when required. To increase the effectiveness 80 of the grip, the surfaces of the jaws coming in contact with the cable may be roughened, if desired.

What I claim as my invention, and desire to protect by Letters Patent, is—

1. A rope or cable grip for haulage purposes comprising an open-sided jaw forming one portion of the grip, a chamber at the lower part of said jaw, having located therein a jaw normally resting on the bottom of the cham- 100

ber, a pivoted lever in contact with the loose jaw provided at one end with two arms for operating the loose jaw and at the other end with a hook substantially as and for the purposes described.

2. A rope or cable grip for haulage purposes comprising in combination an open-sided jaw, a loose jaw arranged in a chamber therein, a pivoted lever provided with arms designed to come in contact with the loose jaw, slotted arms attached to the loose jaw and a connecting-hook attached to the lever for operating the loose jaw substantially as described.

15 3. A rope or cable grip for haulage purposes comprising an open-sided jaw forming one portion of the grip, a chamber at the lower part of said jaw, having located therein a jaw normally resting on the bottom of the chamber, slotted arms formed on the loose jaw embracing a pin passed through the lower portion of the open-sided jaw, guiding-pieces

formed on the loose jaw on either side of the pin and a pivoted lever in contact with the loose jaw provided at one end with two arms 25 for operating the loose jaw and at the other end with a hook substantially as and for the purposes described.

4. A rope or cable grip for haulage purposes comprising an open-sided jaw forming 30 one portion of the grip, a chamber at the lower part of said jaw having located therein a jaw normally resting on the bottom of the chamber, a pivoted lever in contact with the loose jaw provided at one end with a cam-shaped 35 surface for operating the loose jaw and at the other end with a hook substantially as and for the purposes described.

In witness whereof I have hereunto set my hand in the presence of two witnesses.

JOSEPH ASPINALL.
